(57) **CLAIM**

The ornamental design for a tool box with compartment for a level, as shown and described.

DESCRIPTION

FIG. 1 is a perspective view of a tool box with a level compartment in a closed position and thus the level is hidden from view;

FIG. 2 is a left side elevational view thereof;

FIG. 3 is a top plan view thereof;

FIG. 4 is a bottom plan view thereof;

FIG. 5 is a front view thereof;

FIG. 6 is a back view thereof; and

FIG. 7 is a perspective view thereof with a level compartment in an opened position and thus the level exposed and accessible to a user;

FIG. 8 is a view of section 8—8 of FIG. 6, which illustrates the feature of the back view as an indentation; and,

FIG. 9 is a right side elevational view there.

The broken line showing of the level in FIG. 7 is for illustrative purposes only and forms no part of the claimed design. The level is included only to show the use of the level compartment.
